(57) **CLAIM**

The ornamental design for a powered case trimmer, as shown and described.

DESCRIPTION

FIG. 1 is a front and left side perspective view of a powered case trimmer showing my new design;
FIG. 2 is a left side elevation view thereof, of which the right side elevation view is a mirror image;
FIG. 3 is a front elevation view thereof; and,
FIG. 4 is a top plan view thereof, of which the bottom plan view is a mirror image.

1 Claim, 1 Drawing Sheet

FIG. 4
